Wiederholt & Gabbert,
ATTORNEYS:

UNITED STATES PATENT OFFICE.

JOHN MURRAY LEIGHTON, OF BELFAST, IRELAND.

APPARATUS FOR LINING WALLS OF SHAFTS, CAISSENS, AND THE LIKE.

Application filed August 15, 1928, Serial No. 299,712, and in Great Britain September 15, 1927.

This invention relates to an improved method of sinking the lining walls of shafts, caissons, hollow piers, piles and the like.

According to this invention, the structure, 5 or article to be sunk is suspended, or connected to, members capable of suspending it, whereby greater regularity of sinking is obtained and whereby the rate of sinking can be controlled, the suspension members being preferably adjustable and also preferably provided with means for indicating the tension on the suspension members. The essential feature of this method is that the sinking should be continuous to avoid the necessity of overcoming 10 the inertia of a large mass, which has come to rest, in order to set it in motion again, and also to maintain the planes of cleavage between the earth and the moving lining. The clearance cut in the soil below the end of the 15 shaft lining will be such that in the event of any obstacle being encountered which may require special means for its removal the rate of sinking may be slowed up by control of the suspending members to such extent as may be necessary to permit the removal of such obstacle and the resumption of the ordinary excavating methods without the sinking being brought to an entire standstill. Preferably a series of trestles, or the like, would be erected 20 round the shaft with suitable arrangements for suspending and lowering the shaft lining, or other structure, or article. For convenience, all the different structures and articles which might be included under this 25 invention will be hereinafter referred to simply as, shaft lining, which is one example of a structure to be sunk in accordance with the invention. The number of suspension members connected with the trestles will be such 30 that any one may be temporarily disconnected without placing an undue strain on the remainder. The trestles and suspension and lowering members will not necessarily be of sufficient strength to support the entire 35 weight of the finished shaft lining but will be of such strength as will suffice to carry the full weight of the first or several sections of the shaft lining. The total weight capable 40 of being supported by the trestles and suspension members will bear such proportion

to the total weight of the completed shaft lining as will represent, when the suspending members are lowered, a material addition to the load tending to sink the shaft lining and instantly applicable by lowering the suspension members. 55

The invention will now be described with reference to the accompanying drawings whereon is shown, by way of example only, a diagrammatic representation of the sinking 60 of a shaft lining in accordance with the invention.

Referring to the drawings:—

In carrying out the invention in accordance with the example shown on the drawings, the structure, or article to be sunk, in this example the circular shaft lining 1, is suspended from a plurality of trestles 2 arranged at suitable intervals around the shaft and suitably anchored to the ground. In the examples shown, the trestle 2 is anchored to a concrete foundation 3. The shaft lining 1 is suspended from the trestles 2 by means of a screw threaded suspension member 4 which also serves, when required, as a pressure member. The suspension member 4 is connected to the trestle 2 by a member 5 pivoted to the trestle at 5^a and having a hole 5^b through which the suspension or pressure member 4 passes freely, a nut 6 being placed on the screw threaded suspension, or pressure member above the member 5 and a nut 7 placed on the screw suspension, or pressure member 4 below the member 5. An extension or arm 5^c of the member 5 is connected with two tension and pressure meters 8^a and 8^b of any known and suitable type. The space 2^a in the trestle 2 is adapted to receive loading weights when required. The number of trestles 2 would be such that any one may be temporarily disconnected without placing an undue strain on the remainder. The trestles 2 and the suspension members 4 are not necessarily sufficiently strong to support the entire weight of the finished shaft lining 1, but will be of sufficient strength safely to support the full weight of the first or several sections of the shaft lining as previously mentioned. 85 90 95

In operation, in the case of sinking a circular shaft lining 1, the first section 1^a is prefer- 100

ably provided with a cutting edge at the bottom thereof as shown. The section 1^a is first bolted to the suspension members 4 and levelled by adjusting same relatively to the members 5 connecting the suspension members 4 with the trestles 2. Sinking is then commenced and is carried on continuously until the shaft lining 1 has reached the desired depth. The ground within the shaft lining 1 may be excavated by any desired means, and the clearance cut in the soil below the bottom section 1^a of the shaft lining (as indicated at 9) will be such that in the event of any obstacle being encountered and having to be removed, the rate of sinking of the shaft lining 1 may, by control of the suspension members 4, be slowed up thereby to such an extent as to allow of the removal of the obstruction and the resumption of ordinary excavating methods without the sinking of the shaft lining being brought entirely to a standstill. As the shaft lining 1 sinks, section 1^b as shown will be bolted on top of the first section 1^a and so on until the entire shaft has been sunk to the required depth. As the shaft lining sinks there will be friction set up between the earth and the outer surface of the lining and this will react on the suspension member 4 causing it in turn to react on the pivoted member 5 so that the latter, by means of the tension and pressure meters 8^a, 8^b will indicate the extent by which skin friction between the outer wall of the lining and the earth is retarding the sinking of the lining. When a point is reached, indicated on the tension and pressure meters, at which skin friction must be reduced to prevent the sinking of the lining being stopped, then lubricating material, for example water, grease or soft soap, or the like, may be forced through holes 1^c provided in the lining and provided with screw plugs, or the like, which are removable at will. By this means a film of lubricant may be introduced between the earth and the external surface of the shaft lining. The use of the lubricant may be regulated as observation of the tension and pressure meters indicates the necessity for greater or less lubrication. The tension meter 8^b will come into action to indicate tension when the weight of the lining is being supported by the trestle and the lining is sinking by its own weight without the addition of pressure. When the lining is slowed up to such an extent that pressure must be applied, and the trestle has to be used for this purpose, through the medium of the member 5 and pressure member 4, then the nut 7 will be operated and, as required, additional weight may be given to the trestle by loading same with loading material or other ballast, for example stones 10 as shown. When the lining is being lowered without the application of additional pressure, the nut 6 will be used. In addition, or as an alternative, to the application of pressure, weight

may be applied to the shaft lining in the usual manner in order to maintain the desired continuous sinking. Such added weight would only be sufficient to restore the strain on the suspension members 4 to normal and would be very much less than that required to set the shaft lining in motion again if it had been permitted to come entirely to rest. It will be understood that the simple pressure means shown on the drawings is merely by way of example and diagrammatic. Pressure may be applied to the pressure member 4 by screw, hydraulic or any other known and suitable means.

When it is desirable (after the lining has been sunk to the required depth) to restore the full frictional grip of the earth on the shaft lining, then the lubricant used may be one which is soluble in water and by applying water through the hole 1^c, the lubricant may be washed away. Cement grout may then be forced through the holes 1^c and setting to the external wall of the lining and filling up cavities in the soil, will fully restore the frictional grip of the earth on the shaft lining.

The method of sinking a shaft lining, or any other structure, as hereinbefore described, may be employed to sink same into the ground below water and in such cases the trestles 2 may be carried on piles, or the like. Where water is permitted to rise inside the shaft, pipes may be carried up from the holes 1^c before they are submerged so that lubrication may be applied at any desired point.

I claim:

1. Apparatus for sinking a shaft lining into position comprising, supporting trestles, a suspension member carried by each trestle, means connecting each suspension member to the shaft lining, means whereby tension or pressure can be applied to each suspension member so as to regulate the sinking operation and means whereby the tension or pressure on each suspension member is indicated.

2. Apparatus for sinking a shaft lining into the ground comprising, in combination, supporting trestles, screwed members for the lining, a pivoted member on each trestle, means connecting each suspension member to the lining and to a pivotal member, meters carried by each trestle and connected to a pivotal member whereby the tension and pressure on each screwed member is indicated, and screw nuts on each screwed member whereby tension or pressure can be applied thereto so as to regulate the sinking operation.

In testimony whereof I affix my signature.

JOHN MURRAY LEIGHTON. 125
